UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DESIGN FOR A RADIATOR COVER.

Application filed September 2, 1927. Serial No. 23,276. Term of patent 14 years.

To all whom it may concern:

Be it known that I, JOSEPH LEDWINKA, a citizen of the United States, residing at Philadelphia, in the county of Philadelphia, State of Pennsylvania, have invented a new, original, and ornamental Design for a Radiator Cover, of which the following is a specification, reference being had to the accompanying drawings, forming part thereof, wherein—

Figs. 1 and 2 are respectively a front elevational view and a side elevational view of the radiator cover embodying the design.

I claim:

The ornamental design for a radiator cover, as shown.

Signed at Philadelphia, in the county of Philadelphia, in the State of Pennsylvania, this 19th day of August, 1927.

JOSEPH LEDWINKA.
